UNITED STATES PATENT OFFICE

CLAUDE A. LEWIS, OF MEDFORD, MASSACHUSETTS

DESIGN FOR A DESK ORNAMENT

Application filed March 3, 1932. Serial No. 43,060. Term of patent 14 years.

To all whom it may concern:

Be it known that I, CLAUDE A. LEWIS, a citizen of the United States, and a resident of Medford, in the county of Middlesex and State of Massachusetts, have invented the new, original, and ornamental Design for a Desk Ornament, of which the following is a specification.

Reference is to be had to the accompanying drawing forming part thereof, wherein The figure is a perspective view of a desk ornament showing my new design.

I claim:

The ornamental design for a desk ornament substantially as shown.

CLAUDE A. LEWIS.
